UNITED STATES PATENT OFFICE.

WILLIAM M. KELLY, OF JERSEY CITY, NEW JERSEY, ASSIGNOR TO AMERICAN TYPE FOUNDERS COMPANY, OF JERSEY CITY, NEW JERSEY, A CORPORATION OF NEW JERSEY.

PILE-ELEVATING MECHANISM.

Application filed August 6, 1921. Serial No. 490,289.

The present invention relates to printing presses and more particularly to pile elevating mechanism therefor. It comprehends manual means to raise the pile constructed and arranged to permit the operation of automatic pile elevating mechanism without disturbing said manual means. To this end the manual means includes a one-way transmitting device such as a one-way clutch. The invention also includes two manual devices for elevating the pile, one adapted to raise the pile of sheets at a greater speed than the other and either means being operable without actuating the other. The invention also includes improved automatic means for elevating the pile controlled by the height of the pile. All of the foregoing means are disposed at the side of the printing press frame near the top thereof and are simple and dependable.

20 The objects and features of novelty of the invention will be apparent from the description taken in connection with the drawings, in which

25 Figure 1 is a partial side elevation of a printing press equipped with the present invention;

Figure 2 is a partial plan view of the mechanism shown in Fig. 1;

Figure 3 is a sectional elevation taken substantially on the line 3—3 of Fig. 2, and

Figure 4 is a sectional view taken substantially on the line 4—4 of Fig. 3.

Referring to the drawings the form of the invention illustrated includes a pile supporting table 10 supported by brackets 11 vertical- 35 ly slidable on the ways 12 of the side frames 13 of the press. The present invention comprehends means for raising and lowering the pile table 10. As shown the side frames 13 at the top thereof carry a transverse shaft 14 and a sprocket 15 is secured to this shaft adjacent the side frames 13. A chain 16 at its lower end is secured to each of the brackets 11 and passes up over the sprocket wheels 15 and hence depends at the other side of the sprocket, the loose end of the chain being supported in any suitable manner as by being fastened to the member 17, Fig. 1.

50 In the form of the invention illustrated one of the side frames 13 carries a short shaft 18 positioned directly below the transverse shaft 14 and these two shafts are rotatively connected by the gears 19 and 20. In this manner the shaft 18 is connected to the table

10 so that rotation of said shaft effects vertical movement of the table. 55

The shaft 18 projects laterally from the side frame 13 and carries an arm 21 loosely mounted thereon and adjacent thereto a ratchet wheel 22, the latter being secured to the shaft for rotation therewith in any suitable manner as by means of a key 23. Referring to Fig. 1 it will be seen that there is a second arm 24 which is adapted to be oscillated by a cam 25, the arm 24 carrying a roller 24^a in contact with the periphery of the cam for this purpose. The free ends of the arms 24 and 21 are connected by a link 26 so that the oscillation of arm 24 is transmitted to arm 21, the cam moving the parts in one direction, and spring 21^a operative on arm 21 moving them in the other direction. The oscillation of arm 21 is transmitted to ratchet wheel 22 by means of the pawl 27 pivoted at 28 on said arm. Retrograde movement of the ratchet wheel is prevented by a pawl 29 pivoted at 30. A plate 31 is also pivoted on the pin 30 and is provided with an aperture 32 into which projects a pin 33 carried by the pawl 29. The aperture 32 is of greater diameter than the pin 33 to permit the pawl to ratchet over the ratchet teeth. However the two parts are associated so that when the plate is moved slightly in a clockwise direction on its pivot it will raise the locking pawl 29 out of engagement with the ratchet wheel. A latch 34 is adapted to engage with the tail 35 of the plate to hold it in raised position, a spring 36 being provided tending to pull the latch member 34 into engagement with said tail 35. As clearly shown in Fig. 1 the plate 31 projects along under a pin 37 carried by the pawl 27 so that when the plate is raised it strikes the pin 37 and disengages the pawl 27 from the ratchet wheel. In this manner both pawls may be rendered inoperative when desired. 85

From the foregoing it is apparent that the rotation of cam 25 rotates the ratchet wheel 22 step by step, thus elevating the pile supporting table. Means is provided however for controlling this elevating mechanism in accordance with the height of the pile. For this purpose a shaft 38 is rotatably carried on the inside of the frame 13 and has an arm 39 extending out over the top of the pile, as shown in Fig. 2, this arm being secured to the shaft in any suitable manner as by the clamp 100 105

screw 40. At the free end of the arm 39 is a 5 feeler finger 41 adapted to rest on the top of the pile. As the pile decreases in height therefore the finger 41 falls slightly rotating the shaft 38. This shaft also carries an arm 42 projecting through the side frame 13 and being operative on a link 43 the upper end of which is pivoted to a lever 44, the latter being carried by the side frame 13. Another lever 10 45 is operatively connected to the lever 44 by a link 46. Hence up or down motion of the feeler finger 41 through the parts just described will be transmitted to the lever 45 raising and lowering the pin 47 or the free end thereof. The link 26 carries a pin 48 which is positioned so that when the pin 47 is moved 15 downwardly as viewed in Fig. 1, it will come into the path of pin 48 and thus hold the arm 24 at the left hand end of its movement as viewed in said Fig. 1. Thus when the pile is 20 elevated sufficiently the pin 47 is moved into contact with pin 48 and the automatic elevation of the pile is rendered inoperative. The lower end of link 43 rests in a socket in arm 42, the parts being held together by spring 43a.

In addition to the automatic means for elevating the pile just described a manual device is provided and in accordance with this invention this manual device is independent 30 of the automatic means inasmuch as the operation of the automatic means has no effect on the manual device. As shown this manual device includes a worm wheel 49 loosely mounted on the shaft 18 and connected by a 35 one-way clutch to transmit its rotation in one direction only to the ratchet wheel 22. As shown in Fig. 4 the one-way clutch is of the roller type and comprises a spider 50 secured to the hub of the ratchet wheel 22 and a series of wedging rollers 51. The worm wheel 49 meshes with a worm 52 on a shaft 53 disposed substantially parallel with the side frame 13. At its rear end this shaft is provided with a hand wheel 54. When this 40 wheel is turned in the direction indicated by the arrow 55 in Fig. 1 the table is elevated and even if the locking pawl 29 is thrown out of engagement the table will be held in any position by the friction between the 45 worm and worm wheel. However the pitch of the worm is such that if the hand wheel 54 is set spinning rapidly in the direction to lower the table, the weight of the table will automatically continue the lowering, the friction between the worm and worm wheel no 50 longer overcoming the weight of the table. It will be understood that for this lowering operation, the locking pawl 29 must be disengaged from the ratchet wheel 22.

The rate of elevation of the table through the manual means just described is relatively slow. If desired a more rapid manual means may be provided. Thus as shown the shaft 18 carries a handle 56 loosely mounted thereon and having a recess 57 in its hub adapted

to receive a tooth 58 on the sleeve 58' secured to the shaft, when the handle is moved axially on the shaft 18 toward the left as viewed in Fig. 3. It will be observed that the tooth 58 has one side beveled so that relative turning of the worm wheel and handle tends to throw the handle out of engagement with said finger.

It will be understood that cam 25 on shaft 25a is constantly rotated in timed relation 75 with the cycle of movements of the press.

The press with which the present invention is particularly adapted to co-operate is described and claimed in my co-pending application Serial Number 490,290, filed August 80 6, 1921.

Having thus described the invention what is claimed as new and desired to be secured by Letters Patent is:

1. Mechanism of the character described 85 including in combination, a vertically movable pile supporting table, a rotatably mounted member, transmission means between said member and table to transmit motion from one to the other including a one-way clutch 90 and gearing including a driving gear, said gearing constructed and arranged when inoperative to hold the table against lowering and to permit such lowering at a substantially uniform rate when the driving gear is set 95 spinning in the lowering direction, and other means functionally independent of said clutch to actuate the table.

2. Mechanism of the character described 100 including in combination, a vertically movable pile supporting table, a rotatably mounted member, transmission means between said member and table to transmit motion from one to the other including a one-way clutch, and an automatically operated 105 means functionally independent of said clutch to raise said table.

3. Mechanism of the character described 110 including, in combination, a vertically movable pile supporting table, and manually operable means to raise or lower said table, including two meshing gear members, said gears being constructed to hold the table against lowering when the gears are not rotating and when one is set spinning in the 115 direction to lower the table, the lowering will continue automatically at a substantially uniform rate because of the weight of the table.

4. In a sheet feeding mechanism, in combination, a pile supporting table, a shaft 120 adapted, when turned, to raise or lower said table, means controlled by the elevation of the top of the pile to turn said shaft to maintain the top of the pile substantially at a predetermined elevation, a worm wheel, a one-way 125 or over-running clutch to transmit motion from the wheel to the shaft only in the direction to raise the table and permit operation of said automatic means without rotating said wheel, a worm meshing with said worm 130

wheel and manually operable means to turn said worm.

5. Mechanism of the character described including in combination, a vertically movable pile supporting table, manually operable means to raise the table, releasable means holding the table against downward movement, said manual means constructed and arranged when inactive to hold the table against 70 downward movement when the releasable means is released and when set in motion in the proper direction to be actuated by the weight of the table to lower the latter at a substantially constant speed.

10 6. Mechanism of the character described including in combination, a vertically movable pile supporting table, means to elevate said 75 table constructed and arranged when inactive to hold the table against a lowering movement and when set in motion in the lowering direction to be actuated by the weight of the table to automatically continue the lowering at a substantially uniform rate.

7. Mechanism of the character described including, in combination, a vertically movable pile supporting table, means to elevate said 80 table including a worm and wheel having a pitch such that, when the worm is inactive, the table will be held against lowering movement, but when the worm is spun in the direction to lower the table, the lowering will continue automatically at a substantially uniform rate because of the weight of the table.

35 8. Mechanism of the character described including in combination a vertically movable pile supporting table, a rotatable shaft, means 85 operatively connecting said shaft and table, manually operable means to turn said shaft including a one-way clutch, a releasable manually operable means to turn the shaft, and automatically actuated means to turn the 90 shaft step by step.

9. Mechanism of the character described including in combination, a vertically movable 95 table, a rotatable shaft, motion transmitting means connecting said table and shaft, a hand crank operatively connected with said shaft to turn it in one direction only, hand operated means to turn said shaft at a slower speed, automatically actuated means to turn 100 the shaft step by step and releasable ratchet means to hold the shaft against turning in the table lowering direction.

50 10. Mechanism of the character described including in combination a vertically movable pile supporting table, a rotatable shaft 105 operatively connected with said table to raise and lower the same, a wheel secured to said shaft, automatically actuated means operable on said wheel to turn the shaft in table raising direction and manually operable means including a one-way motion transmitting means 110 associated with said shaft.

55 11. In a sheet feeding mechanism, in combination, a pile supporting table, a shaft adapt-

ed, when turned, to raise or lower said table, means controlled by the elevation of the top of the pile to turn said shaft to maintain the top of the pile substantially at a predetermined elevation, a worm wheel, a one-way or over-running clutch to transmit motion from the wheel to the shaft only in the direction to raise the table and permit operation of said automatic means without rotating said wheel, a worm meshing with said worm wheel, and manually operable means to turn said worm, the pitch of the worm and worm wheel being such that the table is normally held against lowering and, when the worm is set spinning in the direction to lower the table, the lowering will continue automatically at a substantially uniform rate because of the weight of the table.

12. Mechanism of the character described including in combination a vertically movable pile supporting table, a rotatable shaft operatively connected with said table to raise and lower the same, a wheel secured to said shaft, automatically actuated means operable on said wheel to turn the shaft in table raising direction, and manually operable means including a one-way clutch operable on the hub of said wheel.

13. Mechanism of the character described including, in combination, a rotatable shaft, a ratchet wheel secured to said shaft, means at one side of said ratchet wheel connecting the shaft and table to raise or lower the latter in accordance with rotation of the shaft, manually operable means disposed on the other side of said wheel to turn said shaft in the raising direction, said manual means including a one-way clutch, and an automatically actuated pawl adapted to turn said wheel step by step.

14. Mechanism of the character described including, in combination, a rotatable shaft, a ratchet wheel secured to said shaft, a vertically movable pile supporting table, means on one side of said wheel connecting the shaft and table so that the latter is raised and lowered by turning the shaft, manually operable means to turn said shaft disposed on the other side of said ratchet wheel and including gearing and a one-way clutch an automatically actuated pawl adapted to turn said wheel step by step, and a second and releasable pawl associated with said wheel to hold said shaft against turning in one direction.

15. Mechanism of the character described including, in combination, a rotatable shaft, a ratchet wheel secured to said shaft, a vertically movable pile supporting table, means on one side of the wheel connecting the shaft and table so that the turning of the shaft raises or lowers the table, manually operable means on the other side of the ratchet wheel to turn said shaft in the raising direction, said manual means including a worm and worm wheel and a one-way clutch, and an automatically actuated pawl adapted to turn said

ratchet wheel step by step, the movement of said pawl being controlled by the height of the pile.

16. In a sheet feeding mechanism, in combination, a pile supporting table, a shaft adapted, when turned, to raise or lower said table, means controlled by the elevation of the top of the pile to turn said shaft to maintain the top of the pile substantially at a predetermined elevation, a worm wheel, a one-way or over-running clutch to transmit motion from the wheel to the shaft only in the direction to raise the table and permit operation of said automatic means without rotating said wheel, a worm meshing with said worm wheel, the pitch of the worm and worm wheel being such that the table is normally held against lowering and, when the worm is set spinning in the direction to lower the table, the lowering will continue automatically at a uniform rate because of the weight of the table, said automatic elevating means including a ratchet wheel, and said ratchet wheel, worm wheel and clutch all being mounted on said shaft.
17. Mechanism of the character described including in combination a vertically movable pile supporting table, means to raise said table including a rotatable cam, an arm actuated by said cam, a ratchet wheel, a pawl operative on said wheel and actuated by said arm, means controlled by the height of the pile to govern the engagement of said arm with said cam, manual means to turn said

wheel including a worm and worm wheel and a one-way clutch interposed between said worm and ratchet wheel.

18. Mechanism of the character described including in combination a vertically movable pile supporting table, means to raise said table including a rotatable cam, an arm actuated by said cam, a ratchet wheel, disposed so that its axis is at substantially the same elevation as the axis of said cam, a second arm, a link connecting said arms, a pawl on said second arm operative on said wheel to actuate the latter and means controlled by the height of the pile to govern the action of said pawl.

19. In a sheet feeding mechanism, in combination, a pile supporting table, a shaft adapted, when turned, to raise or lower said table, means controlled by the elevation of the top of the pile to turn said shaft to maintain the top of the pile substantially at a predetermined elevation, a worm wheel, a one-way or over-running clutch to transmit motion from the wheel to the shaft only in the direction to raise the table and permit operation of said automatic means without rotating said wheel, a worm meshing with said worm wheel, and manually operable means to turn said worm, said automatic means including a ratchet wheel, and said ratchet wheel, worm wheel and clutch all being mounted on said shaft.

In testimony whereof I hereunto affix my signature.

WILLIAM M. KELLY.
